Fig. 1

FIGURE 1 is a top plan view of a packaging tray for produce, embodying my design, a minor portion thereof being shown schematically in dot-dash lines to indicate repetition of the design;

I claim:

The ornamental design for a packaging tray for produce, as shown and described.
